(57) CLAIM

The ornamental design for a combination cigarette lighter, bottle opener, corkscrew and knife, as shown and described.

DESCRIPTION

FIG. 1 is a perspective view of a combination cigarette lighter, bottle opener, corkscrew and knife showing my new design;

FIG. 2 is a side elevational view thereof;

FIG. 3 is an elevational view of the opposite side thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a perspective view showing the lighter in open, operative position; and,

FIG. 9 is a side elevational view showing the bottle opener, corkscrew and knife in operative position.
